BOAT ANCHOR

Anthony James Marshaus, Cleveland, Ohio

Application January 14, 1941, Serial No. 374,407

2 Claims. (Cl. 114—206)

The present invention relates to new and useful improvements in anchors and has for its primary object to provide, in a manner as herein-after set forth, a device of this character which will embed itself firmly in the bottom for securely holding a boat connected thereto.

Another very important object of the invention is to provide an anchor comprising means for absorbing shock and relieving strain when the boat pitches or surges.

Still another very important object of the invention is to provide an anchor of the character described embodying a novel construction and arrangement whereby said anchor may be readily freed from the bottom when it is desired to hoist said anchor.

Other objects of the invention are to provide a boat anchor which will be comparatively simple in construction, strong, durable, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of an anchor constructed in accordance with the present invention.

Figure 2 is an elevational view of the device with portions broken away in vertical section.

Figure 3 is a view in horizontal section, taken substantially on the line 3—3 of Figure 2.

Figure 4 is an elevational view of the lower portion of the anchor, taken at right angles to Figure 2.

Figure 5 is an elevational view of the rod.

Figure 6 is a top plan view of another form of head which may be used.

Fig. 7 is a view in side elevation of the modified head with portions thereof broken away in section.

Referring now to the drawings in detail, it will be seen that the reference numeral 1 designates a rod of suitable metal, said rod also being of any suitable length and diameter. Pivotedly mounted on the upper end portion of the rod 1 is a bail 2 for connecting an anchor line (not shown) to said rod. Fixed, as by welding, on an intermediate portion of the rod 1 is a stop collar 3. Mounted on the lower portion of the rod 1 is a collar 4 which is secured by a pin 5.

Slidably mounted on the rod 1, between the collars 3 and 4, is a head of suitable metal which

is designated generally by the reference numeral 6. The head 6 includes a tubular shank 7 which is slidable on the rod 1 and engageable with the collar 3, said tubular shank comprising an enlarged lower end portion 8 which is substantially conical. Projecting from the portion 8 of the shank 7 are integral, upwardly inclined arms 9 which terminate, at their outer or free ends, in flukes 10.

10 Also mounted on the rod 1, between the collars 3 and 4, is a coil spring 11. The lower end of the coil spring 11 rests on the collar 4. The coil spring 11 is engaged with the head 6 for yieldingly urging said head toward the stop 3. The tubular shank 7 is counterbored, as at 12, for the reception of the coil spring 11.

Threaded on the lower end portion of the rod 1 is a pair of locked nuts 13. Rotatably mounted on the lower portion of the rod 1, between the collar 4 and the locked nuts 13, is a foot 14 in the form of a horizontally elongated, vertical plate of suitable metal. The foot 14 includes an eye 15 at an intermediate point which is journaled on the rod 1.

25 It is thought that the manner in which the device functions will be readily apparent from a consideration of the foregoing. Briefly, when the anchor is dropped the head 6 and the foot 14 rest on the bottom. When pull occurs on the

30 anchor line, the rod 1 moves forwardly through the tubular shank 7, the coil spring 11 is compressed and the arms 9 with the flukes 10 thereon are embedded in the bottom. Of course, only the arms 9 which are lowermost will, as a general rule, be embedded in this manner. Should the boat surge or pitch the shock and strain transmitted to the anchor will be absorbed by the coil spring 11.

35 When it is desired to hoist the anchor the boat is preferably maneuvered to a position substantially over the anchor and the line is slackened to permit the coil spring 11 to move the foot 14 away from the head 6. Then, when the line is pulled upwardly the rod 1 functions as a lever swinging from the foot 14 and in this manner the head 6 is freed with comparatively little effort. By removing the nuts 13 and the collar 4 the foot 14, the coil spring 11 and the head 6 may be expeditiously removed from the rod 1.

40 In Figures 6 and 7 of the drawings there is illustrated a mushroom head 16 of suitable metal which may be slidably mounted on the rod 1 in lieu of the head 6. The head 16 has formed therein a plurality of drain openings 17 for the passage of water and mud. Of course, in the

use of this form of the invention the portion of the mushroom head 16 which is lowermost is embedded in the bottom.

It is believed that the many advantages of a boat anchor constructed in accordance with the present invention will be readily understood and although preferred embodiments of the device are as illustrated and described, it is to be understood that further modifications and changes in the details of construction may be resorted to which will fall within the scope of the invention as claimed.

What is claimed is:

1. An anchor of the class described comprising an anchor head, a rod having an intermediate part slidingly passing through the head and including lower and upper ends the latter for attachment of an anchor cable thereto, an upper stop on the rod, spring means tending to hold the head against the stop and opposing sliding movement of the rod through the head when the cable pulls on the upper end of the rod to

ease the strain on said cable and a bar-like member rotatably connected at an intermediate point on the lower end of the rod, said bar-like member acting as a fulcrum on the lower end of the rod during initial raising of the anchor off the bottom.

2. A boat anchor of the class described comprising a rod having a cable receiving member at its upper end, upper and lower stops on the rod, an anchor head having a tubular part through which the rod passes with the tubular part having a shoulder therein, a spring encircling the rod and having its upper end engaging said shoulder with its lower end engaging the lower stop, and a bar-like member having an intermediate portion pivoted to the lower end of the rod below the lowest stop and forming a fulcrum for the anchor during the first part of the lifting motion in pulling the anchor from the bottom.

ANTHONY J. MARSHAUS.
